HOOD LATCH

Arthur Claud-Mantle, Trumbull, Conn., assignor
to The Bassick Company, Bridgeport, Conn., a
corporation of Connecticut

Application February 4, 1949, Serial No. 74,599

9 Claims. (Cl. 16—128.1)

1

This invention relates to hood latches, and more particularly to latches for so-called dual-tip hood lids, namely, lids that extend across the engine enclosure and can be released and raised at either side.

The hood latch of the present invention can be regarded as a variation or modification of the device described in my application Serial No. 70,827, filed January 14, 1949.

The latch herein disclosed is of a kind in which the lid has fixed pivots disposed laterally and outwardly of the engine enclosure or well, but in some phases of the invention this is not essential.

One of the objects is to simplify and improve the structure of dual-tip hood latches.

Another object is to provide for tighter and more secure latching of the lid to the fixed part of the engine enclosure.

Another object is to provide a hood latch in which fixed pivots are employed for the bolt members, wherein any looseness or play in association with the pivots is eliminated when the lid is in the latched position.

In the accompanying drawings:

Fig. 1 is a top plan view of the hood portion of an automobile equipped with a hood latch embodying my improvements, the hood lid being closed;

Fig. 2 is a side elevation of the parts shown in Fig. 1;

Fig. 3 is a section on line 3—3 of Fig. 1;

Fig. 4 is a cross-sectional view showing on a larger scale certain parts at the right of Fig. 3;

Fig. 5 is a top plan view of the keeper and detent structure shown in Fig. 4, the bolt member being omitted;

Fig. 6 is a top plan view of the bolt member and its mounting shown in Fig. 4, the keeper and detent structure being omitted;

Fig. 7 is a view similar to Fig. 4, showing the lid in raised position;

Fig. 8 is a sectional view showing the side of the lid in raised position with respect to the bolt member;

Fig. 9 is an enlarged bottom plan view of a portion of the lid looking in the direction of the arrows 9—9 of Fig. 2;

Fig. 10 is an enlarged bottom plan view of a portion of the lid looking in the direction of arrows 10—10 of Fig. 2;

Fig. 11 is a detail of the bracket on which the bolt member is mounted; and

Fig. 12 is an end view of the bolt member looking from the left-hand end of Fig. 6, the cross-pin being omitted.

2

In the drawings, the invention is illustrated in connection with an automotive vehicle having an engine compartment or well defined at the sides by upright walls at the top of which are located mud guards which extend in a lateral direction, the walls of the well being notched or cut away to receive pivoted bolt members that have pivots located laterally outside of the well, said bolt members having bolting ends that extend into the well to which the marginal portion of the lid is adapted to be latched. In this form there are two latching and hinging devices associated with each side of the hood, one being near the rear end and the other near the front end, and these devices, located at the same side of the car, have their latching mechanism operable by and from a torsion-rod-swinging device located between the ends of a torsion rod equipped with crank-like latching extremities that cooperate with the bolt members previously mentioned, the torsion-rod-swinging device in turn being operable from a lever device carried by the lid adjacent the rear end of the latter. The torsion-rod-swinging device, operating upon the intermediate portion of the torsion rod, may be of a suitable kind, for example, that shown in the Moore Patent 2,000,245 of May 7, 1935.

In this particular form the bolt member has an upper bail-like part or loop adapted to project upwardly into an apertured keeper bracket carried by the lid and provided in a reinforcing cross strip carried by the lid, and the latching effect is produced by the crank-like end of the torsion rod, the torsion rod being journaled in the keeper portion and the crank-like extremity or detent being adapted to enter the bail-like part from beneath and to engage and secure the bolt member in the manner hereinafter described.

In the drawings, the lid is indicated at 20, the engine well at 21, and the upper parts of the mud guards at 22. The lever device adjacent the rear end of the lid is indicated at 23, the associated longitudinal torsion rod at 24, the crank-like extremities of the torsion rod at 25, and the torsion-rod-swinging device or element operable from lever 23, at 26. The four latching and hinging devices associated with the torsion rod are indicated at 27, the two forward devices 27 being associated with a forward transverse carrier strip and bracket structure, indicated at 28, and the rear devices 27 being associated with a similar but longer carrier strip and bracket structure 29. The four latching and hinging devices 27 are all alike or substantially so, and therefore to a large extent a description of one will suffice.

The bolt member of each latching and hing-

ing device is indicated at 30, the hinge or pivot member for the bolt member at 31, and the bail-like part or loop on the bolt member is indicated at 32.

The rear transverse carrier strip 29 is shown in Fig. 3, and in part in Fig. 4. This strip is suitably connected to the hood lid in a manner to reinforce the same, the connection to the lid being effected by suitable means, as by welding. The strip is preferably made of sheet metal, and at its end adjacent each side margin of the lid it is shaped to provide a bracket 33 with which the bolt member cooperates, said bracket having an approximately horizontal lower panel or leg 35 spaced downwardly from the lid provided with an aperture 34 through which the bail-like part or pilot head 32 can project upwardly in the manner shown in Fig. 4. The bracket 33 of sheet metal provides part of a resilient or springy keeper structure, and another part of this structure is provided by a bent sheet metal member 36 in which the end portion of the torsion rod is journaled, the member 36 having an apertured base 37 through which the bail or pilot member 32 extends, said base 37 being secured against the upper face of the panel or leg 35 by means such as bolts 38. The base 37 is provided with an aperture 38^a somewhat smaller than the aperture provided in the part 35. The member 36 is corrugated or ribbed in order to give it greater strength, and it is bent upwardly from the base portion and then laterally to provide an upper overhanging portion 39, which, in the latched position of the lid, overlies the upper end of the bail or pilot member 32 with a certain amount of clearance. The arrangement is such that the generally U-shaped member 36 is disposed horizontally to rest on its side in the space between the bracket 33 and the upper wall of the lid, with the extremities of the member 36 directed toward the side margin of the lid. The upper part 39 of the member 36 has at its free extremity a bent or rolled-up part 40, which provides a journal for the torsion rod near its crank-like extremity. The bail 32 has parallel upwardly projecting side walls joined together near the top by a crosspin 41, and when the lid is in the latched position the extremity or detent 25 of the torsion rod has the position shown in full lines in Fig. 4, there being a downwardly extending arm portion and an inwardly extending arm portion, the inwardly extending arm portion being directed away from the side of the lid, and being in engagement with the under portion of the crosspin 41 for holding the bolt member within the keeper structure. For centering the bail or pilot in the keeper structure, the edges of the former disposed toward the margin of the lid are preferably curved, as shown in Fig. 4, and the side walls of the bail are preferably arched for centering purposes, as shown in Fig. 12, there being arch-shaped portions which lie immediately below straight portions in which the crosspin member 41 is received. This pin member is preferably shouldered between the opposite walls of the bail and fastened in place by upsetting the ends, as indicated at 42.

As will be seen from Figs. 6 and 12, the body of the bolt member 30 is constructed of sheet metal having parallel side walls integral with the side walls of the bail, and the bolt member has a narrow part 43 located in the engine well, and a wide part 44 located outside of the well. The side walls of the wide part are secured to a mounting bracket 44^a by two pivots 31, these

pivots in this particular case being constituted by pins passing through registering holes in the two members, and having riveted-over or upset ends, indicated at 45. The bolt member not only has the upright side walls previously referred to, but also an integral bottom member 46 which extends substantially throughout the length of the bolt member and creates a member of channeled cross section. The narrow part 43 of the bolt member and the wide part 44 extend at an obtuse angle to each other.

The mounting bracket 44^a, mentioned above, is adapted to be secured in place in a notch in the side wall of the engine well, and has a portion, 15 extending laterally and outwardly from the side wall of the well, in which the bolt member is hinged. The bracket member has parallel side walls 47 to which the bolt member is pivoted in the manner previously described, and the walls 20 47 are interconnected by an upper wall 48. Adjacent the side wall of the engine well the walls 47 are provided with integral laterally bent lugs 49 provided with vertically elongated slots 50 in which are engaged screw members 51 by means 25 of which the mounting bracket is held in place. Usually a layer of metal or other suitable material, indicated at 52, is interposed between the lugs 49 and the side wall of the well. The inner part of the mounting bracket presents an open 30 mouth portion in which the bolt member can operate, this mouth portion being defined at the lower part by integral tongues 53 which extend toward each other and underlie the bolt member. The function of these tongues is to support the bolt member from beneath by engaging 35 it intermediate of its ends, the bolt member when so supported having the position shown in Fig. 8, for example. In this position the part of the bolt member within the engine well is approximately horizontal.

The bail or pilot head 32 is located intermediate of the ends of the side walls of the bolt member which are located within the engine well, and the upper edges of the side walls which are on opposite sides of the bail or pilot head 45 are adapted to make contact with the lower surface of the contact plate provided by the panel 35. When, however, the parts are in the position shown in Fig. 4, the left-hand extremity 50 only of the bolt member makes contact with the panel, the upper edge of the bolt body in such case being disposed at an acute angle to the contact plate. The reason for this will appear later on.

The torsion-rod-swinging device 26, previously mentioned, is of the type shown in the Moore Patent 2,000,245, and comprises a mounting plate 54 mounted on a bracket 55 attached to the inner surface of the lid. As in the patent mentioned, the torsion rod 24 is provided intermediate of its ends with a bent semi-circular part engaged by a member 56 having a swivel connection with the plate 54, indicated at 51. In this particular case the swinging actuating member 56 for turning the rod on its axis is provided with an arm 58 having pivotal connection with a connecting rod 59, the rear extremity of which is operably connected to the lever-type actuating device 23, previously mentioned. The device 23, involving a swinging actuating lever, may be of any appropriate kind for the purpose. In the form illustrated the lever is fulcrumed on the lid intermediate of the ends of the lever by a fulcrum 60, and the connecting rod 59 is pivoted at 61 to an inwardly extending post rigid with one end por-

tion of the lever 23. When the torsion rod is in a position corresponding to the unlatched position of the corresponding latch devices, the lever 23 has the outwardly swung position with reference to the lid shown by the dotted lines in Fig. 10. When, however, the lid is in position for latching, the crank-like extremities of the torsion rod may be moved to the latching position by swinging the lever 23 from the position just indicated to the position shown in full lines in Fig. 10. In Fig. 10 the parts are shown as viewed from the inner face of the lid, and the lever, in moving to the outward position, may move, in part, in a suitable slot or aperture in the lid.

The inner edge of the upper wall 48 of the mounting bracket which is adjacent the mouth portion of the bracket is adapted to act as a stop limiting the upward swing of the bolt member.

As the crank extremities of the torsion rod normally depend in a position such as shown in Fig. 8 when the torsion rod is in the released position, the hood may be closed down by a downwardly tilting motion, which causes the upper keeper structure to move down over the head or bail of the bolt member. At this time the bolt member is held in its lowermost position by the stops 53, and the lower contact plate of the keeper structure will rest upon the upper edges of the bolt member body. Then, by actuation of the torsion rod, the lid can be latched at the side in question. In doing this the extremity of the crank of the torsion rod is swung from the dotted-line position of Fig. 4 to the full-line position, the tip of the crank extremity moving up against the lower surface of the crosspin. As the tip of the crank presses upwardly against the crosspin, there is a springing and downward twisting movement of the upper part of the resilient keeper element 36, while at the same time there is a lifting and swinging of the bolt member until its upper body edges make contact at their extremities with the upper keeper structure at the left-hand side of the bolt head or bail, as shown in Fig. 4. Not only is the keeper member 36 sprung or tensioned to a certain extent, but likewise the upper bracket 33, which is likewise of springy material. The inner extremity of the bolt member contacts the keeper structure, while the upper edge of the bolt member extends at an acute angle to the contact plate of the keeper. Under the conditions stated the inner end of the bolt has a pivot point or region against the contact plate, and the bolt member can be cammed upwardly while the upper edge of the bolt and the lower face of the contact plate remain at an acute angle to each other, thus insuring ample winding or energizing of the resilient torsion rod to bring the lid to a tightly closed position. The torsion rod is effectively held in the latched position by means such as described in Patent 2,000,245, or like means, with the torsion rod under considerable tension or twisting stress.

In the latching of the lid, as just described, the side of the lid is pulled downwardly and the underlying portion of the bolt pulled upwardly. As the bolt is pulled upwardly, with its inner end in contact with the keeper plate to act as a pivot, the bolt has sufficient swing in reference to the pivot point just mentioned to move its right-hand end (Fig. 4) upwardly sufficiently to take all play or looseness out of the hinge-pin connection of the bolt with its mounting bracket.

It is understood that when the lid is latched at both sides, the condition of the latch device opposite that of Fig. 4 will be the same as disclosed in Fig. 4. In other words, the lid will be sup-

ported upon the points of contact provided at the inner extremities of the two bolt members. When, however, the latch device opposite the one shown in Fig. 4 is released, the acute angle condition previously mentioned will no longer exist, and as the lid is raised from the side opposite Fig. 4, the upper edge of the bolt member will be in contact with the contact plate at both sides of the bolt head, as shown in Fig. 7.

It will be seen from the foregoing description that, in latched position, the lid is very effectively clamped in place, and the devices previously described, arranged at opposite sides of the hood, interact with each other in an effective manner to prevent the fluttering of the hood on rough roads. The torsion rod can be very fully twisted in latching the lid so as to obtain a full closing, and the torsion rod is effectively held in the latched position. The interaction between the bolt member and the keeper and detent structures is very effective, eliminating any looseness in this part of the device which would cause rattling, and in the latched position any looseness or play is taken out of the pivotal connection between the bolt member and its mounting. The device, moreover, is simpler and less expensive than previous devices provided for the same general purposes.

It will be noted that the bolt member is a shallow member depthwise with respect to the engine well, the upper obtuse angle between its two inclined straight portions or arms being of the order of 135°. This is a feature of simplicity and advantage in comparison to previous hinging members used in dual-tip hoods.

By reference to Figs. 1, 2 and 9 it will be apparent that the mounting plate 54 for the rod-turning means is substantially horizontally disposed at the side of the lid between the lid ends.

Various modifications and changes may be made in the structure without departing from the principles of the invention or the scope of the claims.

What I claim is:

1. In a latch mechanism for a dual-tip hood lid, the combination of a keeper and detent structure adapted to be carried by the lid adjacent its margin, and an upwardly movable bolt member adapted to be carried by the fixed part of the engine enclosure and adapted to cooperate with said keeper and detent structure comprising a bolt fixedly hinged at a point laterally and outwardly of the engine enclosure, said bolt having substantially straight portions located at an obtuse angle to each other and connected substantially end to end and respectively located within and without the enclosure, the part within the enclosure having intermediate of its ends a protruding bail-like part to cooperate with the keeper and detent structure by penetrating and being latched in a keeper opening, said bolt having an upwardly facing channel providing sheet-metal side walls and said bail-like part being constituted partially by portions of said walls and partially by a crosspin extending between said walls, the part of said bolt located without the engine enclosure being a wide part and the part within the engine enclosure being relatively narrow.

2. In latch mechanism for a dual-tip hood lid, the combination of a keeper and detent structure adapted to be carried by the lid adjacent its margin, and an upwardly movable bolt member adapted to be carried by the fixed part of the engine enclosure and adapted to cooperate with

said keeper and detent structure comprising a bolt which in the closed position of the lid is approximately horizontal and has a fixed pivot at the end farthest from the longitudinal axis of the engine enclosure and is provided with a straight part connected substantially end to end to another straight part extending at an obtuse angle to the first straight part, said latter part being provided with a protruding bail-like element extending upwardly to cooperate with the keeper and detent structure by penetrating and being latched in a keeper opening, both of said straight parts being formed as upwardly facing channels, and means engaging said bolt at the underneath part adjacent the junction of said straight parts for supporting the bolt in the position mentioned, said last-named means being formed as a part of a mounting bracket to which the bolt is hinged.

3. In latch mechanism for a dual-tip hood lid, the combination of a keeper and detent structure adapted to be carried by the lid adjacent its margin, and an upwardly movable bolt member adapted to be carried by the fixed part of the engine enclosure and adapted to cooperate with said keeper and detent structure comprising a bolt which in the closed position of the lid is approximately horizontal and has a fixed pivot at the end farthest from the longitudinal axis of straight part connected substantially end to end to another straight part extending at an obtuse angle to the first straight part, said latter part being provided with a protruding bail-like element extending upwardly to cooperate with the keeper and detent structure by penetrating and being latched in a keeper opening, and means engaging said bolt at the underneath part intermediate of its ends for supporting the bolt in the position mentioned, said last-named means being formed as a part of a mounting bracket to which the bolt is hinged, said mounting bracket being provided with a mouth and said supporting means being constituted by stop members at the lower part of said mouth.

4. In a latch mechanism for a dual-tip hood lid, the combination of a keeper adapted to be carried by the lid adjacent its margin comprising a bracket member substantially in the form of a U resting on its side and having in the lower part thereof a keeper aperture spaced downwardly from the lid adapted to receive a bolt part, a detent member journaled in the upper part of said member comprising a torsion rod having a depending latching extremity, and a bolt member adapted for hinging at one end to a fixed part of the engine enclosure at a point laterally and outwardly of the lid, said bolt member having relatively straight portions arranged at an obtuse angle to each other and having the end of one substantially meeting the end of the other, the portion remote from the bolt hinge having an upwardly extending bail-like part located intermediate of its ends and adapted to enter the keeper aperture and to be engaged interiorly by the depending latching extremity of said torsion rod to latch the lid.

5. In a latch mechanism for a dual-tip hood lid, the combination of a keeper structure and a detent structure adapted to be carried by the lid, the keeper structure comprising a bracket having upper and lower arms and an aperture in the lower arm spaced downwardly from the lid adapted to receive a bolt part and the detent structure comprising a torsion rod journaled in the upper part of said bracket and having adjacent the

bracket a depending crank-like extremity, and a bolt having two substantially straight portions at an obtuse angle to each other connected substantially end to end adapted for location respectively within and without the engine enclosure, the portion outside of the engine enclosure being hinged to the fixed structure of the automobile to swing in a vertical plane, said portions having an upwardly facing channel and the portion of said bolt inside of the engine enclosure having intermediate of its ends an upwardly projecting head adapted to enter said keeper aperture and be latched therein by the depending extremity of said torsion rod, said last-named bolt portion having at the upper part thereof and at the respective sides of the bolt head a body edge which in the latched position extends at an acute angle to the opposing portion of the keeper structure.

6. In a latch mechanism for a dual-tip hood lid, the combination of a keeper structure and a detent structure adapted to be carried by the lid adjacent its margin, the keeper structure comprising an apertured plate spaced downwardly from the top of the lid and the detent structure comprising a torsion rod with a crank-like extremity, the torsion rod being journaled at a point substantially above the keeper aperture, and an upwardly movable bolt member adapted for hinging to the fixed part of the engine enclosure having an upwardly facing channel and relatively straight parts connected substantially end to end and disposed at an angle of substantially 135° to each other, one of said parts being hinged to the fixed part of the engine enclosure and the other part carrying a bolt head intermediate of the ends of said other part adapted to enter the keeper aperture and be latched therein by engagement of said head by the crank-like extremity of the torsion rod, the innermost of the bolt parts being adapted to extend beyond said aperture and underlie said plate.

7. In a latch mechanism for a dual-tip hood lid, the combination of a keeper and detent structure adapted to be carried by the lid adjacent its margin, and an upwardly movable bolt member adapted to cooperate with said keeper and detent structure and to be fixedly hinged at a point laterally and outwardly of the engine enclosure, said bolt member having a portion operating within the enclosure which is substantially straight and in the latched position of the hood is substantially horizontal, said portion being formed as an upwardly facing channel and being provided intermediate of its ends with an upwardly extending bail structure including the sides of the channeled member, said bail being adapted to cooperate with the keeper and detent structure by extending into and being latched in an aperture formed in a keeper plate, the portion of said bolt member outside of the engine enclosure being formed as an upwardly facing channel and being hinged at its outer end to a fixed part and in the latched position of the hood extending upwardly from the outer end of the first portion to the hinge at a relatively slight inclination, the bolt portion operating within the enclosure being adapted to extend beyond said aperture and underlie said plate.

8. In a latch mechanism for a dual-tip hood lid, the combination of a keeper and detent structure adapted to be carried by the lid adjacent its margin, a bolt member adapted to be fixedly hinged at a point laterally and outwardly of the engine enclosure and having a straight portion which in the latched position of the hood is sub-

stantially horizontally disposed within the engine enclosure, said straight portion being provided with a protruding bail-like part to cooperate with the keeper and detent structure by penetrating and being latched in a keeper opening, and a downwardly inclined bracket member to which said bolt member is hinged extending downwardly and inwardly from the hinge and provided with a portion through which said bolt member extends, said bracket portion being adapted to support the bolt member from beneath the latter.

9. In a latch mechanism for a dual-tip hood lid, the combination of a keeper adapted to be carried by the lid adjacent its margin comprising a member substantially in the form of a U resting on its side with its terminals disposed toward a side of the lid and having a keeper opening in the lower side spaced downwardly from the lid body, a detent member journaled in the upper part or side of the said U-shaped member adjacent the terminal of said side comprising a torsion rod having a depending latching extremity, and a bolt member comprising a laterally ex-

5

10

tending substantially straight portion underlying the lid having an upstanding part adapted to extend into and be latched in said keeper opening and also comprising a second portion joined to the first and having an end pivot for hinging to a fixed part spaced laterally and outwardly from the lid.

ARTHUR CLAUD-MANTLE.
